UNITED STATES PATENT OFFICE.

WALTER A. HAYNES, OF EVERETT, ASSIGNOR TO HIMSELF AND STEPHEN BADGER, OF CHARLESTOWN, MASSACHUSETTS.

DESIGN FOR MATCH-SAFE.

Specification forming part of Design No. 6,974, dated November 4, 1873; application filed October 1, 1873.
[Term of Patent 7 years.]

To all whom it may concern:

Be it known that I, WALTER A. HAYNES, of Everett, of the county of Middlesex and State of Massachusetts, have invented a new, useful, and ornamental Design for a Match-Safe; and do hereby declare the same to be fully described in the following specification and represented in the accompanying drawings, of which—

Figures 1 and 2 are perspective views of the said safe.

The safe has two compartments, A B, one for holding matches and the other for the stumps thereof. The body of the safe in general form is a rectangular prism, with flanges *a a a a* and *b b b b* at its corners and lower edges. Each of the upright flanges *a* is arranged at an angle of forty-five degrees with the next contiguous side and end of the body, and is curved or fluted down its front, as shown. The bottom of the match-receptacle is a plane for part of its width, and next curves upward, as shown at C, the bottom of the stump-re-

ceptacle being a plane. The form of the bottom of the match-compartment renders it both useful and ornamental. The safe at its bottom is recessed, as shown at *g*, or provided with a supporting-flange, formed and projected from the bottom in manner as shown at *h*.

I claim—

1. The design or external form or configuration of flanged match-safe, as shown and described, such involving the rectangular prism with the flutes and flanges, its corners, and also the flanges of its lower edges, all arranged as shown.

2. The configuration of the bottom of the match-safe, such consisting in the recess *g* and the counter-curve C, arranged as shown, with the rest or upper and lower plane surfaces of the bottom.

W. A. HAYNES.
